UNITED STATES PATENT OFFICE.

GEORGE OKUYAMA, OF MADISON, WISCONSIN.

STREET-INDICATOR.

1,102,679.

Specification of Letters Patent.

Patented July 7, 1914.

Application filed October 14, 1913. Serial No. 795,093.

To all whom it may concern:

Be it known that I, GEORGE OKUYAMA, a Japanese subject, residing at Madison, in the county of Dane, State of Wisconsin, have invented certain new and useful Improvements in Street-Indicators; and I do hereby declare the following to be a full, clear, and exact description of the invention, such as will enable others skilled in the art 10 to which it appertains to make and use the same.

This invention relates to street indicators for railway cars and has for an object to provide a novel mechanism for transferring 15 a band step by step from a supply roll to a receiving roll in such a manner as to bring fresh parts upon which the streets are printed to view.

A further object of the invention is to 20 provide a device of this character which will be inexpensive to manufacture, strong and durable in construction, and will be formed of a few parts that will not easily get out of order.

25 With the above objects in view the invention consists of certain novel details of construction and combination of parts hereinafter fully described and claimed, it being understood that various modifications may 30 be made in the minor details of construction within the scope of the appended claims.

In the accompanying drawing illustrating 35 this invention:—Figure 1 is a front elevation of the device. Fig. 2 is a side elevation of the device. Fig. 3 is a longitudinal sectional view of the device taken on the line 3—3 Fig. 2. Fig. 4 is a cross sectional view of the device taken on the line 4—4 Fig. 3. Fig. 5 is a cross sectional view of 40 the device taken on the line 5—5 Fig. 2. Fig. 6 is a fragmentary sectional view showing the position of the cord when the band supply has been taken up by the receiving roll.

45 Referring now to the drawing in which like characters of reference designate similar parts, the device is shown to comprise a casing 10 within which is supported a supply roll 11 and a receiving roll 12, the rolls 50 being journaled one above the other and having their respective shafts 13 and 14 projecting at one end through the casing and there being equipped with respective retarding springs 15 and 16 for preventing too free 55 rotation of the rolls. A band 17 is wound upon the supply roll and is trained for

wardly and downwardly over guide rollers 18 and 19 and thence rearwardly and fixed to the receiving roll 12. The band is equipped at intervals with printed names of streets at 60 which the railway car makes stops, that portion of the band which is disposed between the guide rollers being visible through a sight glass 20 in the front wall of the casing, and as will presently be described the 65 receiving roll is advanced step by step whereby to successively bring into registration with the sight glass the names of the various streets at which the railway car makes stops.

70 For actuating the receiving roller I provide a ratchet lever 21 that is pivoted on a stub shaft 22 outside of the casing, the stub shaft extending into the interior of the casing and being equipped therein with a 75 gear 23, the ratchet lever carrying a spring pressed pawl 24 which operatively engages a ratchet wheel 25 on the stub shaft. Said gear 23 meshes with a pinion 26 carried on the shaft 27 of a drum 28 which is cylindri- 80 cal in outline and is provided spirally with a cord receiving groove 29. Fixed on the receiving roll is a drum 30 which is frusto-conical in outline, that is, it tapers from the receiving roll toward the adjacent end of the casing, and is provided with a spiral cord receiving groove 31 within which a cord 32 is wound, the free end of the cord being directed from the smaller end of the drum up to the overlying end of the cylindrical drum 90 29 and secured in the groove of the latter.

95 A cord 33 is attached to the ratchet and forms means whereby the car conductor may rock the ratchet lever whereby to actuate the drum 29 and wind the cord thereon from the drum 30 whereby the latter is rotated and rotates the receiving roll 12 which winds thereupon the band 17. Since it is necessary to provide that a uniform length of the band be passed at each step actuation of the lever 100 between the guide rollers, the frusto-conical drum 30 above described has been designed to provide for this by actuating the receiving roller through a lesser degree of arc each step as the diameter of the supply 105 on the supply roll decreases, as will be understood. A spring 34 is secured to the ratchet lever and to the casing to return the ratchet lever to normal position after each actuation.

110 In operation the conductor will pull the cord 33 just after the car leaves a street

where it has made a stop so that the printed name of the street where the next stop is made is advanced into registration with the sight glass and may be viewed by the passengers. It is obvious that other printed matter besides the names of streets may be displayed on the band without departing from the spirit or sacrificing any of the advantages of the invention.

10 From the above description it will be seen that I have provided an extremely simple street indicator for railway cars, such indicator being formed of a few inexpensive parts that will not easily get out of order.

15 What is claimed, is:—

A street indicator including a casing, a supply and a receiving roll therein, a band wound upon said supply roll and secured to be taken up by said receiving roll, a 20 ratchet and pawl actuating means, a cylindrical drum having a spirally grooved pe-

riphery, said drum being actuated by said ratchet and pawl means, a substantially frusto-conical drum on the shaft of said receiving roll having the large end directed 25 toward said receiving roll, said frusto-conical drum being provided with a spiral groove, a cord wrapped about said frusto-conical drum in said groove and being directed from the small end of said drum and 30 secured in the groove of said cylindrical drum, said cord being wound upon said cylindrical drum during actuation thereof and serving to rotate said receiving roll through a constantly increasing arc of movement at 35 each step actuation.

In testimony whereof, I affix my signature, in the presence of two witnesses.

GEORGE OKUYAMA.
